UNITED STATES PATENT OFFICE.

PETER B. SEARCY, OF SMITHVILLE, TEXAS.

CAN-OPENER.

1,377,286.

Specification of Letters Patent. Patented May 10, 1921.

Application filed September 16, 1920. Serial No. 410,584.

To all whom it may concern:

Be it known that I, PETER B. SEARCY, a citizen of the United States, residing at Smithville, in the county of Bastrop and 5 State of Texas, have invented certain new and useful Improvements in Can-Openers, of which the following as a specification.

This invention relates to can openers and particularly to the class of can openers employed for removing the covers from shoe 10 polish boxes.

The primary object of the invention is to provide an opener which will not require the use of rivets, openings in the material, or 15 any other means whereby air may enter the can.

Other objects of the invention will appear upon consideration of the following detail description and accompanying drawings, 20 wherein:—

Figure 1 is a side elevation of the can without the opener attached.

Fig. 2 is a perspective view of the member from which the opener is formed.

Fig. 3 is a perspective view of the member folded into the form necessary to provide the opener.

Fig. 4 is a side elevation of the can with the opener attached.

Referring to the drawing by numerals, the 30 can 1 is of conventional form and is provided with a removable cover 2, the edge of which rests upon a lip 3 extending around the can in the usual manner. The cover 2 is 35 formed with an extension ear or lug 4 integrally formed with the cover and extending from the edge thereof. A longitudinal slot 5 is formed in the material and is in alinement with the edge of the cover as 40 shown to advantage in Fig. 1. The extension 4 is also provided with a circular opening 6. When this extension 4 is bent up to the position shown by dotted lines in Fig. 1 and by full lines in Fig. 4, the slot 5 permits 45 communication with the annular lip 3 from the space between the upturned extension and the side of the cover.

The blank form shown in Fig. 2 from 50 which the opener is constructed consists of an elongated strip of suitable metal having each end shaped to provide a cam 7 and 8, the curved edges of which are on opposite sides with respect to each other as shown. Each longitudinal edge of the strip is pro-

vided with a lug 9 and 10 and these are 55 adapted to be laterally bent from the strip to form finger pieces for permitting operation of the opener. To form the opener, the blank form is bent at each end on the lines indicated at 11 and 12 and the can portions are then bent upon themselves as 60 shown in Fig. 3 so that they are in close proximity to each other but are sufficiently spaced from the folded portion to permit the cams to be extended through the opening 6 65 in the extension 4. When thus assembled, the cams 7 and 8 are lodged in the space between the extension 4 and the surface of the covers. Then by grasping the members 9 and 10 with the fingers and rotating the 70 opener in the opening 6 one of the cams will forcibly engage the annular lip 3 by being thrust through the slot 5 and the cover will thereby be forced upwardly and the same 75 readily opened.

Minor changes may be made in the details of construction without departing from the spirit of the invention or the scope of the claims hereunto appended.

What I claim is:—

1. In combination with a receptacle having an annular lip at its upper edge and a cover adapted to engage the lip, an extension formed on the cover provided with an opening and a longitudinal slot in longitudinal alinement with the edge of the cover, an opener comprising means to be mounted in the said opening and including a pair of oppositely disposed cams to be lodged between the said extension and the cover, the 85 said means including finger lugs to be engaged by the fingers of the user for imparting a rotary movement to the opener whereby one of the cam members may engage the lip through the said slot to force the cover 90 upwardly from the lip.

2. In combination with a receptacle having an annular lip at its upper edge and a cover adapted to engage the lip, an extension formed on the cover provided with an opening and a longitudinal slot in longitudinal alinement with the edge of the cover, an 100 opening comprising means to be mounted in the said opening and including a pair of oppositely disposed cams to be lodged between the said extension and the cover, the said 105 means including finger lugs to be engaged by the fingers of the user for imparting a rotary

movement to the opener whereby one of the cam members may engage the lip through the said slot to force the cover upwardly from the lip, the said means including an elongated strip having the cams formed on the end thereof, the said strip being folded whereby contacting intermediate portions will be lodged in the said opening to provide

a pivot in the opening for the said means when the cams are to be rotated. 10

In testimony whereof I have affixed my signature in the presence of two witnesses.

PETER B. SEARCY.
